DESIGN FOR A PORTABLE LAMP

Alvin B. Mayer, St. Louis, Mo., assignor to Aray
Manufacturing & Supply Corp., St. Louis, Mo., a corporation of Missouri

Application September 3, 1940, Serial No. 94,760

Term of patent 14 years

To all whom it may concern:

Be it known that I, Alvin B. Mayer, a citizen of the United States, residing at the city of St. Louis, State of Missouri, have invented a new, original, and ornamental Design for a Portable Lamp, of which the following is a specification, reference being had to the accompanying drawing, forming part thereof.

Fig. 1 is a perspective view of a portable lamp showing my new design; and

Fig. 2 is an elevational view showing the end opposite that towards which Fig. 1 is taken.

I claim:

The ornamental design for a portable lamp, as shown.

ALVIN B. MAYER.
